UNITED STATES PATENT OFFICE.

ALBERT L. CRANDALL, OF BUFFALO, NEW YORK, ASSIGNOR TO FRANK M. CAMPBELL, OF ROCHESTER, NEW YORK.

CASTER SOCKET.

Application filed April 17, 1920. Serial No. 374,641.

To all whom it may concern:

Be it known that I, ALBERT L. CRANDALL, a citizen of the United States, residing at Buffalo, in the county of Erie and State of New York, have invented certain new and useful Improvements in Caster Sockets, of which the following is a specification.

My invention relates to improvements in 10 caster sockets for bedsteads and other articles of furniture.

In casters now in use, a self-expanding member having flexible portions adapted to impinge against the inner surface of a bedstead post or against the inner surface of a 15 large bore provided in an article of furniture is invariably employed; but these flexible members lose their inherent resiliency and the caster becomes loosened within the bedstead post or bore of the article in which 20 it is inserted, thus allowing the caster to wobble and making it hard to move the article about.

Casters which are loosely inserted, or so 25 inserted that there may be lateral play, will move out of proper position under the weight of the article to which they are attached, with the result that the rollers of the caster will not roll freely and will grind into carpets, and wear away the fibers of 30 the wood if resting directly upon a wooden floor.

My invention has for its object to overcome these objections, and to this end it is so constructed that when inserted into a bedstead post or into a bore in some other article of furniture, it will be securely wedged within the post or bore, as the case may be, and will maintain the stem of the caster in a 35 fixed position, although allowing it to rotate 40 to permit the caster to adjust itself when moving the article of furniture. By securely wedging the caster socket of my invention within the post or bore of an article of furniture it is unyieldingly retained or 45 positively locked within the article of furniture, in contradistinction to the usual form of caster socket in which dependence is placed upon a spring arm or arms or spring members, which are adapted to be yieldingly 50 retained against the inner surface of the bed post or bore of the article of furniture but which, when the roller of the caster strikes a depression in or elevation on the

floor, or a depression in a carpet or rug, or the edge of a rug, will yield under the lateral strain applied to the stem of the caster, with the result that the socket will become loosened and permit the entire caster to assume an angular partly-withdrawn position or work itself completely out of the 60 bed post or bore of the article of furniture.

A further object of my invention is to provide a socket for the stem or spindle of the caster which has impinging or locking elements adapted to firmly grip the 65 inner surface of the bedstead post or the bore of another article of furniture, as the case may be, and thus prevent both rotary and longitudinal movement of the socket under all conditions of use.

With these and other objects in view, the invention consists in the employment of a mechanically-expanded device capable of being increased or diminished in diameter so that the socket with the 70 caster secured thereto can be easily inserted into a receiving bore of an article of furniture and be tightened within the bore and as readily loosened and removed from the bore.

It further consists in the novel features 80 of construction and in the arrangement and combination of parts to be hereinafter described and more particularly pointed out in the subjoined claims.

In the drawings:—

Fig. 1 is a side elevation of my improved 85 caster socket having a caster inserted therein, the socket being inserted into a corner post of a bedstead shown in vertical section.

Fig. 2 is a central vertical section through 90 a corner post of a bedstead with my improved socket inserted therein.

Fig. 3 is a detached perspective view of the expandible locking member.

Fig. 4 is an enlarged cross section taken 95 on line 4—4, Fig. 1.

I have shown my improved caster socket inserted into the corner post 5 of a bedstead. This post is preferably cylindrical in cross section and open at its lower end, for the reception of my improved socket designated by the numeral 6. This socket is carried up and inserted into the post 5 with the caster 7, which is of the usual construction having the bifurcated roller-receiving 100 portion 8 forming an upwardly facing

shoulder 9, a pintle 10 fastened into the two spaced arms of said bifurcated portion, a roller 11 rotatable on said pintle between said arms and a stem or spindle 12 extending 5 upwardly from the shoulder 9.

The socket has a sleeve 13 provided with an actuating element 14 in the form of an outwardly projecting flange at its lower end. By preference, said actuating element is 10 formed by a disk threaded onto the lower end of the sleeve 13 with diametrically opposite portions of the disk cut away, as at 15, to provide two parallel sides by means of which it may be rotated with the sleeve, 15 either by hand or by the use of a wrench or other suitable tool applied to the parallel sides 15 of said disk or actuating element. The disk and the lower end of said sleeve bear against the upper surface or shoulder 20 9 of the roller-receiving portion 8. Loosely surrounding the sleeve at the lower end thereof and forming part of the socket is a wedging element or cone 16 which rests upon said disk. The upper end of the sleeve is 25 externally threaded, and applied to this upper threaded end is a wedging element or cone 17 which is adjustable on the sleeve, for a purpose to presently appear, and which also forms part of said socket.

Surrounding the sleeve 13 and portions of the cones 16, 17 and forming part of said socket is a locking member 18. This locking member is formed of a flexible strip of metal 19 having impinging or locking elements 20 fastened thereto, each of said locking elements being formed of a strip of metal of heavier gage than the flexible material 19 and having the opposite ends thereof bent around the upper and lower ends of 40 said flexible strip of metal, the extremities of the locking elements being bent and bearing against the inner surface of the flexible metallic strip. These locking elements may therefore be said to be formed of rigid members constructed of suitable bar material having rebent ends so that the ends of said locking elements are securely fastened to the flexible metallic strip 19. It is apparent that two, or more than three of these 45 locking elements may be employed without departing from the spirit of this invention, and while I have also shown a construction in which the locking elements are formed of material which is flat in cross section, it is to be understood that under the principle involved, in which locking elements are carried by a flexible support, as the strip 19 may be termed, the cross sectional formation of these locking strips may be changed. 50 I, however, consider a locking element formed of bar material which is flat in cross section to have special advantages over some other forms, in that the outer exposed angles or corners of these locking elements are 55 comparatively sharp and will bite into the

metal of the bedstead post or other material in which the socket-receiving bore may be formed, as best shown in Fig. 4.

With the locking member provided with three locking elements, they are spaced substantially equal distances from each other, and when inserted into a bedstead post are spaced equi-distantly around an imaginary circle drawn within the sectional outline of 70 the bedstead post. 75

By rebending the material from which these locking elements are formed, the upper and lower ends thereof are rounded, as at 21, and these rounded portions engage the upper and lower cones 16 and 17, respectively. 80

The wedging element or cone 16, by reason of its being in contact with the actuating element or disk 14 may rotate with said disk when rotating the latter and therefore 85 it may be found advantageous, from a point of economy in manufacturing, to form said wedging element or cone integral with said actuating element or disk.

Preparatory to inserting the socket with 90 its supported caster into the post, the cones 16, 17 are spaced a sufficient distance apart to enable the locking member to be contracted around the sleeve 13 so that all parts thereof lie fully within a circle having a 95 diameter smaller than the interior diameter of the post, but these cones are preferably spaced so that the locking member has a sliding fit with the post and therefore causes the rounded ends of the locking elements to 100 create sufficient friction between such ends and the cones 16, 17 to prevent rotation of the upper cone when rotating the actuating disk 14 and sleeve 13 to which said disk is secured. Therefore, the upper end of the 105 sleeve 13 will be threaded into the upper cone a greater distance when rotating said actuating disk, with the result that said cone is drawn downwardly, thereby causing outward movement of the flexibly connected 110 locking elements, resulting in the outer corners of these locking elements being forced against the internal surface of the post, and where the metal of the post or material in which the socket may be formed is softer 115 than the material from which these locking elements are formed, said corners will bite into the surrounding wall and assure retention of the socket and caster within the post or other bore without the possibility of rotary or longitudinal movement and with assurance that there will be practically little play sidewise of the stem of the caster.

Moreover, where it is desired to eliminate all play sidewise of the caster, it is simply 125 necessary to make the stem 12 of the caster of such a diameter that it will snugly fit within the sleeve 13.

The sleeve 13 with its actuating member 14, which may be formed integral if desired, 130

and the cones 16 and 17, constitute the 5 caster supporting member around which the expandible locking member is arranged and by which it is carried, thus the device is complete and may be inserted within the bore of a bedstead post or other article of furniture and be easily locked therein.

Having thus described my invention, what I claim is:—

10 1. The combination with a caster having a spindle, of a caster socket through which said spindle is passed, said caster socket having a supporting member including a rotatable actuating element, and an expandible locking member surrounding said supporting member and being adapted to be expanded against the wall of a socket-receiving bore upon rotating said actuating element.

20 2. The combination with a caster having a spindle, of a caster socket comprising a caster support through which said spindle is passed and which has a wedging element and means embodied within its construction 25 for moving said wedging element lengthwise and a locking member carried by said supporting member against which said wedging element acts to cause said locking member to forcibly bear against the wall 30 of a socket-receiving bore.

3. The combination with a caster having a spindle, of a caster socket comprising a supporting member through which said spindle is passed and which has a wedging 35 element thereon and means embodied within its construction to move said wedging element lengthwise, said caster socket including a flexibly-connected locking element co-acting with said wedging element and 40 adapted to be forced outwardly against the wall of a socket-receiving bore.

4. The combination with an article of furniture having a socket-receiving bore, of a caster socket comprising a supporting 45 member arranged axially in said bore, and having a rotatable element against which said article of furniture bears; a caster supported by said supporting member and rotatable therein, and a locking member 50 surrounding said supporting member and adapted to impinge against the wall of said bore upon rotating said rotatable element.

5. The combination with an article of furniture having a socket-receiving bore, of a 55 supporting member arranged axially within said bore and having a wedging element thereon, a caster having a stem extending through said supporting member, means to prevent displacement of said stem from said 60 supporting member, and a plurality of flexibly connected locking elements spaced around said supporting member and adapted to forcibly bear against the wall of said bore.

65 6. The combination with an article of fur-

niture having a socket-receiving bore, of a 70 caster socket comprising a supporting member arranged axially within said bore and having an axial passage therethrough, a wedging element adjustable lengthwise thereon, and vertically-disposed elongated locking elements flexibly connected together and spaced around said supporting member with said wedging element in contact with said locking elements to force the latter outwardly against the wall of said bore.

7. The combination with an article of furniture having a socket-receiving bore, of a 80 caster socket comprising a sleeve rotatable within said bore, a cone surrounding the lower end of said sleeve, a second cone vertically-adjustable on the upper end of said sleeve and a locking member having vertically-disposed locking elements flexibly connected together and arranged to surround 85 said sleeve, and a caster having a stem extending through said sleeve and an upwardly-facing shoulder at the lower end of said stem against which the lower end of said sleeve bears.

90 8. The combination with an article of furniture having a socket-receiving bore, of a 95 caster having an upwardly facing shoulder and a stem extending into said bore from said shoulder, a sleeve arranged axially within said bore and having the stem of said caster extending therethrough, an actuating element at the lower end of said sleeve for rotating the latter, a cone surrounding the lower end of said sleeve and 100 resting upon said actuating element, a cone threaded onto the upper end of said sleeve and being adjustable lengthwise thereon, and an expandible locking member surrounding said sleeve and adapted to be 105 forced outwardly by said cones when rotating said actuating element and sleeve.

9. The combination with an article of furniture having a socket-receiving bore, of a 110 caster having an upwardly facing shoulder and a stem extending upwardly from said shoulder, a sleeve arranged axially within said bore and having said stem extending therethrough, said sleeve having an actuating element at its lower end for rotating 115 said sleeve, said actuating element resting upon the shoulder of said caster, a cone surrounding the lower end of said sleeve and resting upon said actuating element, a cone threaded onto the upper end of said sleeve 120 and adjustable thereon, and a metallic element partly surrounding said sleeve and having a plurality of rigid locking elements secured thereto, opposite ends of said locking elements bearing against said cones, said locking elements being forced outwardly against the wall of said bore when rotating said actuating element and sleeve and causing downward movement of said adjustable 125 cone.

10. The combination with an article of furniture having a socket-receiving bore, of a caster having an upwardly facing shoulder and a stem extending upwardly from said shoulder, a sleeve having a projecting flange at its lower end accessible to rotate said sleeve, a wedging element at the lower end of said sleeve above said flange, a vertically-adjustable wedging element at the upper end of said sleeve, and a locking member having a flexible portion partly surrounding said sleeve and a plurality of vertically-disposed rigid metallic members fastened to the exterior thereof against which said wedging elements act to cause outward movement thereof against the surrounding wall of said bore.
11. The combination with an article of furniture having a socket-receiving bore, of a supporting member arranged axially within said bore and having spaced wedging surfaces thereon, and a locking member surrounding said supporting member and comprising a plurality of vertically-disposed rigid metallic elements flat in transverse section and a strip or sheet of flexible metal to which said locking elements are secured, each of said locking elements having opposite ends rebent and clamped over the upper and lower ends of said flexible sheet or strip, the rounded lower and upper ends of said locking elements lying in contact with the spaced wedging elements on said supporting member.
12. The combination with an article of furniture having a socket-receiving bore, of a caster having an upwardly facing shoulder and a stem extending upwardly from said shoulder, a sleeve arranged axially within said bore through which said stem is passed, said sleeve being externally threaded at its upper and lower ends, an actuating disk threaded onto the lower end of said sleeve, a cone surrounding the lower portion of said sleeve and resting upon said actuating disk, a cone adjustable on the upper threaded end of said sleeve, a flexible strip or sheet of metal partly surrounding said sleeve, and

metallic vertically-disposed rigid strips of metal having their opposite ends bent around the upper and lower portions of said flexible strip to lie against the inner surface thereof, the extremities of said vertically-disposed rigid strips bearing against the upper and lower cones, said rigid strips being adapted to be forced outwardly upon rotating said actuating disk and sleeve and drawing said upper cone downwardly and having their outer corners impinging against or biting into the wall of said bore.

13. The combination with an article of furniture having a socket-receiving bore, a supporting member arranged axially within said bore and comprising a rotatable portion including a sleeve threaded at one end and a wedging element on the threaded end of said sleeve, a caster having a stem extending through said sleeve, and a locking element surrounding said sleeve and adapted to be forced outwardly against the wall of said socket-receiving bore when rotating said rotatable portion.

14. The combination with an article of furniture having a socket-receiving bore, a supporting member arranged axially within said bore and comprising a rotatable portion including a sleeve and a cone at the lower end of said sleeve and a longitudinally movable portion in the form of a cone threaded onto the upper end of said sleeve, and a locking member surrounding said supporting member and adapted to be forced against the wall of said socket-receiving bore by said cones when rotating said rotatable portion.

15. In combination with an article of furniture, a caster socket unyieldingly retained in said article of furniture and having a caster provided with a roller and with a stem which is arranged axially in said socket, said stem being free to rotate within said socket to cause the roller of the caster to swing in a circle or in an arc of a circle.

In testimony whereof I affix my signature.

ALBERT L. CRANDALL.
